(57) **CLAIM**

The ornamental design for a folding chair as shown and described.

DESCRIPTION

FIG. 1 is a top, front and right side perspective view of a folding chair showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1;

FIG. 11 is an enlarged view of portion 11 in FIG. 2;

FIG. 12 is a top, front and right side perspective view showing the folding chair in a disassembled state; and,

FIG. 13 is a top, front and right side perspective view showing the folding chair in a folded state.

The evenly dashed broken lines in the drawings illustrate portions of the folding chair that form no part of the claimed design.

The long dash-short dash broken lines in FIGS. 1, 2, and 9-11 illustrate the boundaries of the enlarged views and form no part of the claimed design.

1 Claim, 13 Drawing Sheets
